Primary Examiner—Philip S. Hyder**[57] CLAIM**

The ornamental design for a toy action figure, as shown and described.

DESCRIPTION

FIG. 1 is a front elevational view of the toy action figure showing my new design;

In FIG. 2, the phase "say no to drugs" is for illustrative purposes only and forms no part of the claimed design;

FIG. 2 is a rear elevational view thereof;

FIG. 3 is a right side elevational view thereof;

FIG. 4 is a left side elevational view thereof; and,

FIG. 5 is a top plan view thereof.
